Primary Examiner — Darlington Ly*Assistant Examiner* — Daniel J Domino(74) *Attorney, Agent, or Firm* — Sughrue Mion, PLLC(57) **CLAIM**

The ornamental design for a display screen with animated graphical user interface, as shown and described.

DESCRIPTION

FIG. 1 is a front view of a first image of a first embodiment of a display screen with animated graphical user interface showing our new design;

FIG. 2 is a second image thereof;

FIG. 3 is a second embodiment thereof showing a first image;

FIG. 4 is a second image thereof;

FIG. 5 is an image of FIG. 1 without the electronic device on which the display screen is provided;

FIG. 6 is an image of FIG. 2 without the device;

FIG. 7 is an image of FIG. 3 without the device; and,

FIG. 8 is an image of FIG. 4 without the device.

The appearance of the graphical use interface transitions sequentially between the images shown in FIGS. 1 and 2 in the first embodiment and FIGS. 3 and 4 in the second embodiment. The process or period in which one image transitions to another forms no part of the claimed design. The broken lines showing an electronic device illustrate environmental subject matter, whereas the broken lines showing a display screen and elements of the graphical user interface illustrate portions of the article. No subject matter depicted in broken lines form part of the claimed design.
